DESIGN FOR A RUG

William Brown, Scarsdale, N. Y.

Application June 26, 1939, Serial No. 85,694

Term of patent 3½ years

To all whom it may concern:

Be it known that I, William Brown, a citizen of the United States of America, residing in the city of Scarsdale, county of Westchester and State of New York, have invented a new, original, and ornamental Design for a Rug, of which the following is a specification, reference being had to the accompanying drawing, forming part thereof. The drawing shows a portion of a rug showing my new design, the dot and dash lines indicating one half section thereof, the other half of the rug is like that disclosed, the leaf motif continuing in the same relation as shown.

I claim:

The ornamental design for a rug, substantially as shown and described.

WILLIAM BROWN.
